UNITED STATES PATENT OFFICE

160,684

DISH DRIER

Clara J. Altman, Detroit, Mich.

Application February 27, 1950, Serial No. 8,168

Term of patent 14 years

(Cl. D49—1)

To all whom it may concern:

Be it known that I, Clara J. Altman, a citizen of the United States, residing at Detroit, State of Michigan, have invented a new, original, and ornamental design for a Dish Drier, of which the following is a specification, reference being had to the accompanying drawing, forming a part hereof.

Fig. 1 is a perspective view of a dish drier showing my new design.

Fig. 2 is a view taken from the upper left of Fig. 1. The stand base is shown broken off for convenience of illustration.

Fig. 3 is a view taken from the lower right of Fig. 2.

I claim:

The ornamental design for a dish drier, as shown.

CLARA J. ALTMAN.
